No. 893,252.

PATENTED JULY 14, 1908.

G. H. KRAMER.

MOLDER'S FLASK.

APPLICATION FILED JAN. 29, 1908.

UNITED STATES PATENT OFFICE.

GEORGE H. KRAMER, OF DAYTON, OHIO.

MOLDER'S FLASK.

No. 893,252.

Specification of Letters Patent.

Patented July 14, 1908.

Application filed January 29, 1908. Serial No. 413,258.

To all whom it may concern:

Be it known that I, GEORGE H. KRAMER, a citizen of the United States, residing at Dayton, in the county of Montgomery and State of Ohio, have invented certain new and useful Improvements in Molders' Flasks; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

This invention relates to new and useful improvements in molders' flasks and has for its object to provide means for protecting the wood flask from being destroyed or injured from the run-out of molten metal. In 20 addition to the means for thus preserving the wood flask, the same is also reinforced and made stronger, and thus enables the flask to be lighter by using less wood in its construction; or in other words, the side and 25 end panels of the flask may be reduced in thickness without endangering the same to warpage.

Preceding a detail description of the invention, reference is made to the accompanying drawings, of which—

Figure 1, is a perspective view of a molder's flask with parts appearing in section. Fig. 2, is a cross sectional view of one side of the flask, in a vertical plane, and showing a 35 slight modification in the construction of the essential features of the invention.

In a detail description of the invention, similar reference characters indicate corresponding parts.

1 and 2 designate respectively, the upper and lower portions of the flask, otherwise termed the cope and drag portions of said flask, which rest upon a base board or pallet 3. The mold is formed in the usual manner by cope and drag sand 4 and 5; the above briefly describes an ordinary form of two-part flask, which parts are united in the usual manner by dowel pins or otherwise, such as clamps, etc. Secured to the adjacent edges 40 of the two parts 1 and 2 of the flask, are metallic frames; the metallic frame for the upper or cope portion of the flask is of a construction to provide two flanges 6 and 7 which embrace the inner vertical sides and 45 by the lower horizontal edges of said upper portion of the flask, to which portion said me-

tallic frame is rigidly secured by means of counter-sunk screws 10 which penetrate openings in the flange portion 7 and extend into the sides and ends of the flask perpendicularly. The said metallic frame so united to the upper portion of the flask has an inwardly-extending flange portion 8 substantially in a plane with the outwardly-extending flange portion 7, and from the lower side 50 of said inwardly-extending flange 8 there is a downwardly-projected rib or bead 9 which may be semi-circular in cross section or it may be pointed as shown in the drawings. The metallic frame for the lower or drag portion 55 of the flask is likewise provided with an outwardly-extending flange portion 7' and a downwardly-extending flange portion 6', which parts of flanges engage the upper horizontal edges of the drag portion of the flask 60 and the inner vertical sides similar to the metallic frame of the upper portion of the flask. This lower frame is secured to the lower or drag portion of the flask by countersunk screws 10 similar to the manner of securing the upper metallic frame.

The lower metallic frame is minus the inwardly-extended horizontal flange 8 and the downwardly-projected bead 9 which are features of the upper metallic frame, but 65 said lower metallic frame has an upwardly extended flange 11 which the upper metallic frame does not possess. This upwardly-extending flange 11 on the lower portion of the flask engages the metallic frame on the 70 upper portion of the flask substantially in a plane with the perpendicular flange 6 on said upper metallic frame. The cope and drag sand 4 and 5 inclose on both sides the inwardly-extended flange 8 of the upper 75 metallic frame, and it will be observed the bead or rib 9 is embedded in the drag sand 5 and will thus act as a barrier to any out-run of the molten metal that might be disposed to run out of the mold between the 80 adjacent faces of the sand. The molten metal is thus prevented by this downwardly-projected bead or rib 9 from running out and into contact with the sides or ends of the two parts of the flask at the only points where 85 such metal is liable to escape from the mold. As before intimated, the cross sectional shape of the bead or rib 9 may vary from the pointed shape shown in the drawings, without interfering with the function of said bead 90 or rib, which, is as before stated, to intercept any out-run of the molten metal from the 95

mold. The upwardly-extended flange 11 of the lower metallic frame enables a proper fitting of the two parts of the flask at all times, especially when wear by constant usage, tends to cause an unevenness in the fit of the two parts of the flask. These upper and lower metallic frames are provided with a suitable number of apertured ears 12 for the insertion of a similar number of 10 dowel pins 13 by means of which the two parts of the flask are secured together. The modified construction shown in Fig. 2, is substantially the same as that shown in Fig. 1, the only difference being in the omission 15 of the upwardly-extending flange 11 on the lower metallic frame. In this modified construction, the horizontal portions 7 of the angle irons engage each other directly, owing to the omission of the upwardly-extending flange 11 on the lower frame. The inner perpendicular flanges 6 and 6' on the metallic frames, protect the inner sides of the flask from any possible contact with the molten metal, and in addition to this, 20 the flask is reinforced and strengthened to an extent which enables a lighter construction of the flask by the use of wood of less thickness than is otherwise possible.

While I have shown and described two 30 metallic angle iron frames in a two-part flask, it will be understood that these angle iron frames may be employed in connection with flasks having a greater number of parts, for example, a three-part flask or a four-part 35 flask.

I claim:

1. In a molder's flask, a two-part flask, metallic angle frames secured to the adjacent edges of said two-part flask and extending 40 vertically on the inner sides thereof, one of said metallic angle frames extending inwardly in a plane with the adjacent surfaces of the sand and provided with a bead or rib lying in a plane at right angles to said inwardly-extended portion and adapted to prevent the molten metal from running out of the mold between the adjacent surfaces of the sand.
2. In a molder's flask, a two-part flask,

50 metallic angle frames secured to the adjacent edges of the two parts of said flask, one of said metallic frames having an inwardly-extended portion lying parallel with and between the adjacent surfaces of the sand, said inwardly extended portion being provided 55 with a bead or rib extending at right angles therefrom and adapted to penetrate the portion of the sand lying in the lower portion of the mold, and the other of said metallic frame being provided with a vertically-extending flange adapted to engage the first-named metallic frame and to support the upper portion of the flask.

3. In a molder's flask, the combination 60 with a two-part flask, of a metallic angle frame secured to the upper section of the flask and embracing the inner vertical sides and the lower horizontal edges of said upper flask portion, said frame having an inwardly extending flange provided with a downwardly-projected bead, a metallic frame 65 secured to the lower portion of the flask and having flanges extending at right angles to embrace the inner vertical sides and the upper horizontal edges of said flask portions, 70 said metallic frames having means thereon lying on the outside of the flask and adapted to secure the two parts of the flask together.

4. In a molder's flask, the combination 75 with the parts of the flask, of metallic angle frames secured to the adjacent edges of the parts of the flask and embracing the inner sides of the parts of the flask adjacent to the edges, one of said angle frames having an 80 inwardly-extended portion which lies between the sand in the upper and lower portions of the flask, said inwardly-extended portion being provided with a bead projecting from its lower side and which is adapted to prevent the out-run of metal, substantially 85 as specified.

In testimony whereof I affix my signature, in presence of two witnesses.

GEORGE H. KRAMER.

Witnesses:

MATTHEW SIEBLER,
R. J. McCARTY.
